(57) CLAIM

The ornamental design for a “handle for lid for article of cookware,” as shown and described.

DESCRIPTION

FIG. 1 is a front perspective view of a “handle for lid for article of cookware” incorporating the design of my invention.

FIG. 2 is a top view thereof.

FIG. 3 is a bottom view thereof.

FIG. 4 is a side view thereof.

FIG. 5 is another side view thereof.

FIG. 6 is a front view thereof; and,

FIG. 7 is a rear view thereof.

The part of the drawings shown in phantom lines depicts the environment of my new design and forms no part of the design.
